UNITED STATES PATENT OFFICE.

HENRY SMITH, OF PHILADELPHIA, PENNSYLVANIA.

FASTENER FOR WEARING-APPAREL.

1,311,924.

Specification of Letters Patent.

Patented Aug. 5, 1919.

Application filed November 26, 1918. Serial No. 264,131.

To all whom it may concern:

Be it known that I, HENRY SMITH, a citizen of the United States, and a resident of Philadelphia, in the county of Philadelphia and State of Pennsylvania, have invented certain new and useful Improvements in Fasteners for Wearing-Apparel, whereof the following is a specification, reference being had to the accompanying drawings.

10 My invention relates to a novel type of fastener, which, in a certain sense, may be considered as a substitute for a button-hole and externally visible button; while still retaining the normal appearance of the latter 15 devices, my improvements being peculiarly appropriate for the fastening of a coat, where it is desired to preserve the normal appearance, but they can be utilized for shoes, gaiters, or indeed any article where 20 meeting edges are to be detachably secured.

In the accompanying drawings, Figure I, represents a view, in elevation, of the proximate edges of a coat-front, provided with my device, the parts being shown in open 25 position.

Fig. II, is a similar view showing the proximate edges of the coat overlapping and the parts in a closed position.

Fig. III, is a longitudinal section on the 30 line III, III, of Fig. II.

Fig. IV, is a detail sectional view illustrating the method of attaching the button.

The proximate edges of the garment, such as a coat front, are represented at 1, and 2, 35 respectively, the part 2, being provided with an elongated slot, such as an ordinary button-hole 3. Opposite to the location of the button-hole, I apply on the part 1, an externally projecting loop 4, preferably of 40 non-elastic cord, of such color and so attached to the fabric, as to be relatively inconspicuous, when the two parts of the coat-front are open. In the form shown, the loop is applied upon the external face of 45 the garment, since this is the most convenient location.

On the inner side of the fabric of the part 2, and preferably between the fabric proper and the lining 7, I insert an elastic strip 8, 50 suitably secured in position, as by stitching 9, at the rear portion, and at, or near, the front extremity of said strip, which normally should lie opposite to the slot 3, I attach a hook 10, whose opening faces toward the rear extremity of the strip. Upon 55 that surface of the elastic strip which is op-

posite to the point of attachment of the hook 10, I provide means for conveniently grasping the elastic strip for insertion and detachment of the hook, and in order to preserve the characteristic appearance of a button and button-hole fastening and to conceal the end of the strip and also the hook, I prefer to employ an ordinary coat-button 12.

A convenient construction whereby the hook and button may be secured to the elastic strip, is illustrated in Fig. IV. As therein shown, the hook 10, is formed with a shank 11, the outer end of which is tubular. After 60 assembling, the protruding tubular end of the shank 11, is rolled or pressed over the face of the button 12, and thereby permanently united thereto, the strip 8, being at the same time securely pinched between 65 the base of the hook and the back of the button.

The attachment for the button 12, as will be seen by reference to Fig. III, extends through the button-hole 3, and thus the button and the hook opposite thereto are free to move throughout a range corresponding to the length of the button-hole 3.

When it is desired to fasten the garment, the proximate edges may be overlapped, as 85 shown in Figs. II, and III, the elastic strip stretched, and the hook 10, made to engage within the loop 4. The stretching is readily performed by grasping the button 12, with the hand. Upon releasing the button from 90 the hand, the elastic strip springs back to a normal position, thus insuring the permanent engagement of the loop 4, by the hook 10, and the button 12, may thus assume the position which may be considered as a normal 95 one within the button-hole 3. Detachment can obviously be effected by the reverse movement.

I am, of course, aware that the use of hooks upon elastic strips is not new, and I 100 make no broad claim to such a device, but, so far as I am aware, the combination above described, which conserves the normal appearance of a button and button-hole effect of fastening, which can be applied to any 105 ordinary garment, and which at the same time provides a yielding attachment, free from all of the disadvantages of ordinary button fastenings and which is inconspicuous when in open position, is new.

I wish it to be understood that I use the term "loop" simply as indicative of a part

capable of being engaged by a hook and without restriction of the character of such part, and furthermore, that I do not restrict myself to any particular locality for attachment of said loop, it being only necessary that it should be capable of engaging the hook and that the hook should be so mounted as to be capable of reaching it when the proximate edges of the garment are to be secured to one another.

10 I also use the term "button," simply as a convenient one to indicate any external member which may serve the purpose of affording a means for grasping the elastic strip and stretching it, and which, if desired, may also conceal the end of the strip, and preserve the normal appearance of any ordinary button and button-hole fastening.

I claim:

- 20 1. In combination with the proximate edge portions of an article of apparel; a loop mounted upon one of said portions adjacent to the edge thereof; the other of said portions being provided with a slot; an elastic member secured at one extremity to said last mentioned portion and having a free end capable of extension to the region of said slot; a hook mounted upon the free
- 25

portion of said elastic member and adapted to engage said loop; and a button also mounted upon said elastic member to overlie said slot; substantially as set forth.

2. In combination with the proximate edge portions of an article of apparel; a loop mounted upon one of said portions adjacent to the edge thereof; the other of said portions being provided with a slot; an elastic member secured at one extremity to said last mentioned portion and having a free end capable of extension to the region of 40 said slot; a hook mounted upon the free portion of said elastic member and adapted to engage said loop; a button also mounted upon said elastic member; and means whereby said button and said hook are connected 45 to one another and to the elastic member, by an attachment which extends through the slot, substantially as set forth.

In testimony whereof I have hereunto signed my name at Philadelphia, Pennsylvania, this seventh day of November, 1918.

HENRY SMITH.
